UNITED STATES PATENT OFFICE

JOHN W. MACDONALD, OF WILKINSBURG, PENNSYLVANIA

TOY CANNON

Application filed June 5, 1928. Serial No. 283,009.

This invention relates to gas cannons and more particularly to gas cannons adapted for use as toys.

All of the gas cannons known to me that are adapted for use as toys are provided with a combustion or explosion chamber, wherein the explosive mixture is generated. This is done by admitting acetylene or hydrogen to the explosion chamber which mixes with the oxygen contained therein for forming an explosive mixture, or the explosion chamber is provided with a communicating water chamber adapted to receive a quantity of gas forming material, such as powdered calcium carbide for forming acetylene which mixes with the oxygen or air in the explosion chamber to form an explosive gaseous mixture.

Either of these constructions is undesirable because the products of combustion remain in the explosion chamber which is also the gas forming chamber. This necessitates thorough ventilation of the combined explosion chamber and gas forming chamber between each operation or firing of the cannon; also the type of cannon provided with a combined gas forming and explosion chamber having a communicating water chamber is further undesirable due to the fact that the residuum of the gas forming medium collects on the side walls of such water chamber. It is therefore necessary that such chamber be cleaned often and because of the compact and cramped arrangement, access to the interior of the water chamber for cleaning is obviously very difficult.

One object of this invention is to provide a gas cannon having a chamber separate from the explosion chamber in which the explosion takes place for forming the explosive mixture.

Another object of this invention is to provide a gas cannon having a gas mixture generating chamber and an explosion chamber and means for permitting the gas mixture to flow from the generating chamber to the explosion chamber.

Another object of this invention is to provide a gas cannon having a gas mixture generating chamber, an explosion chamber, means for permitting the gas mixture to flow

to the explosion chamber and means for preventing the products of combustion in the explosion chamber from gaining access to the gas mixture generating chamber.

Another object of this invention is to provide a gas cannon having the above characteristics, wherein the gas mixture generating chamber is provided with a water chamber that may be easily and readily removed and cleaned.

A further object of this invention is to provide a gas cannon having the above characteristics, wherein the gas mixture generating chamber is adapted to extend into the associated water chamber for forming a water seal about the lower portion of the generating chamber.

A still further object of this invention is to provide a gas cannon having the above characteristics, wherein the gas mixture generating chamber is provided with a magazine for containing a supply of gas forming medium and means for charging the chamber with a predetermined amount of such gas forming medium.

Other objects of the invention lie in the novel construction and combination of parts that will be made apparent throughout the description of the invention, one embodiment of which is illustrated in the accompanying drawings, wherein; Figure 1 is a perspective view of a gas cannon embodying the invention; and Fig. 2 is a longitudinal sectional view of the device in Fig. 1.

The cannon comprises in general a support base 11, a barrel 12 having portions 13 and 34 connected by a baffle like portion 14, a removable breech block or gas mixture generating chamber 16 provided with a cover within which is formed a magazine 17 for containing a gas forming medium such as calcium carbide, measuring and charging means 18 located below the magazine 17 for charging the chamber with a predetermined amount of the gas forming medium and an independent removable water chamber 19 adapted to receive the lower end of the breech block 16 for forming a water seal as at 21.

The base 11 may be so constructed as to have a bottom 22, sides 23 and end portions 24.

for bracing and strengthening the sides 23. Disposed above the bottom 22 is a supporting member 25 adapted to support the water chamber 19. The inner end of member 25 is provided with an upstanding wall 26 for limiting the inward movement of the water chamber or container 19. The sides 23 are connected together with a top portion 27 for further strengthening the structure in general. Between the portion 34 and the top portion 27 is disposed a tubular tapered support 28 adapted to receive the breech block or gas generating chamber 16 which is also tubular and tapered substantially the same as the support 28. The breech block 16 is provided with a projection 29 which is adapted to engage a cut away portion 31 in the top edge of the support 28. The projection 29 is adapted to cooperate with the cut away portion 31 for limiting the rotation of the breech block 16 within the support 28.

The breech block 16 is also provided with a projection 32 extending outwardly and forward thereof, the purpose of which will hereinafter be described.

The inner side of the support 28 forms a back wall 33 for the enlarged portion 34 of the barrel 12 which forms the explosion chamber. This back wall is provided with an opening or port 35 which is adapted to register with an opening 36 in the block or chamber 16 when the latter is in one position and upon rotation thereof to another position, the opening or port 35 is closed. The position of the opening 36 when the breech block 16 is rotated to close the opening or port 35 is shown by dotted lines in Figure 2. The explosion chamber or enlarged portion 34 of the barrel 12 is provided with an opening or touch-hole 37 for admitting a spark or any means for igniting the explosive mixture therein.

Between the magazine 17 and the top of the breech block 16 is provided a pair of spaced horizontal partitions 38 and 39. These partitions are provided with openings 41 and 42, respectively, and between these partitions is disposed the measuring and charging means 18 comprising a member 43 having an opening 44 therethrough. Member 43 is slidably disposed between the partitions 38 and 39 and provided with a stop 45 for limiting its outward movement and a stop 46 for limiting its inward movement.

The measuring and charging means 18 is operable to receive a measured quantity of carbide in the chamber-like opening 44 when it registers with opening 42 in plate or portion 39, and to transfer this measured quantity to a point where it can be conveyed by gravity to the water chamber 19. Such conveying of the measured charge by gravity takes place when the member 43 is moved to the position shown in Fig. 2, where, it will be observed, the opening or chamber 44

registers with opening 41. The opening 41 fixes the position in which the charge may be conveyed by gravity.

When it is desired to charge the cannon, the member 43 is pulled outwardly by its handle 47 until the stop 45 comes in contact with the adjacent surface of the magazine 17 at which time, the opening 44 in the member 43 registers with the opening 42 in the partition 39 permitting a predetermined amount of the gas forming medium contained in the magazine 17 to fall into the opening or measuring chamber 44. The member 43 is then pushed forward until the stop 46 comes in contact with the stop 29, at which time the opening 44 registers with the opening 41 in the partition 38. When the opening or measuring chamber 44 registers with the opening or passageway 41, the measured quantity of carbide or gas forming material falls by gravity through the opening 41 and the hollow breech block 16 into the water chamber 19. The end of the breech block 16 extends below the water or fluid level in container 19 whereby a water or fluid seal is formed therefor at 21; the acetylene or gas which is formed rises into the breech block 16 and passes through the openings or ports 36 and 35 into the explosion chamber 34.

When the gas enters the explosion chamber 34 it combines with the oxygen of the air therein so as to form an explosive mixture. So long as the breech block 16 is in such a position that the openings 36 and 35 register, one with the other, the projection 32 prevents access of ignition means to the opening or touch-hole 37 and prevents the firing of the cannon until the chamber 16 is rotated in a clockwise direction a distance sufficient to close the opening 35. Since the opening or port 35 is closed when the explosion takes place, the products of combustion formed in the combustion chamber 34 are excluded from the breech block 16. The rotative movement of the breech block 16 is predetermined by the cooperating stop member 29 on the block 16 and the cut-away portion 21 on the top of the support 28.

To remove the container 19 for cleaning, the breech block 16 is moved or lifted vertically until the lower end thereof is above the top of the container. The container 19 may then be removed and cleaned.

Since the breech block 16 and the support 28 are tapered, the cannon is not rendered inoperative in the event that products of combustion are deposited between the block and the support, because the block is movable vertically. Therefore, if deposits are formed the block 16 may be moved vertically until sufficient clearance is provided that will permit rotation of the block.

One advantage of the present construction is that the cannon may be fired more rapid-

ly than gas cannons of this type heretofore provided. Another advantage is the provision of a separate water chamber that may be readily removed and easily cleaned of the residue of the gas forming medium which collects on the side walls of the chamber. Another advantage is the novel magazine and charging device which renders the device more cannon like. Other advantages are to be found in the present construction such as the simplicity of the design, small cost of manufacture and the novel manner in which the cannon is adapted to be operated.

While I have illustrated and described but one embodiment of the invention, it will be apparent to those skilled in the art, that certain changes, modifications, substitutions, additions and omissions may be made in the device, without departing from the spirit and scope of the appended claims.

What I claim as new and desire to secure by Letters Patent is:—

1. A cannon having a stationary explosion chamber and a turnable gas mixture generating chamber, the gas generating chamber being adapted to permit access to the explosion chamber when in one position and to prevent access thereto when in another position.

2. A gas cannon having a stationary explosion chamber, a relatively movable gas mixture generating chamber, means for generating a gas mixture in the last said chamber, means for transferring such mixture to the explosion chamber and means for preventing access of the product of combustion of the explosion chamber to the explosive mixture generating chamber.

3. A gas cannon having a stationary explosion chamber, a relatively movable gas mixture generating chamber, means for generating an explosive mixture in the gas generating chamber, means for transferring such mixture to the explosion chamber, means for preventing access of the products of combustion of the explosion chamber to the gas mixture generating chamber, and means for preventing firing of the cannon so long as access is had between the two chambers.

4. The combination in a toy gas cannon of a barrel having an explosion chamber, a gas generating chamber adjacent thereto, a magazine adapted to feed a gas forming medium into said gas generating chamber, a sliding partition between said chamber and said magazine provided with means for charging the gas generating chamber with a predetermined amount of the gas forming medium.

5. The combination in a toy gas cannon, of an explosion chamber open at each end, a gas generating chamber adjacent thereto and adapted to open into and to close the explosion chamber upon rotation thereof, means for limiting the rotatable movement of said chamber and means for charging the gas gen-

erating chamber with a predetermined amount of a gas forming medium.

6. The combination in a toy gas cannon, of a barrel having an explosion chamber, a gas generating chamber having an opening in one side associated therewith, means for rotating said chamber for opening and closing a passage between said explosion chamber and said gas generating chamber.

7. The combination in a toy gas cannon of a barrel having an explosion chamber, a gas generating chamber having one end sealed with water, means for admitting into said chamber a predetermined amount of a medium forming gas upon coming in contact with water, and means for rotating said chamber to permit and to prevent the generated gas passing into the explosion chamber.

8. A gas cannon having an explosion chamber, a gas forming chamber adjacent to one end of said explosion chamber, means for generating gas in said gas forming chamber, and means for transferring the gas to the explosion chamber.

9. A gas cannon comprising a chamber in which gas may be exploded, a gas generating chamber adjacent to the explosion chamber, a removable water container communicating with the explosion chamber, a source of gas liberating material mounted on the cannon, and a measuring device for admitting measured quantities of said material to the water container.

10. A gas cannon comprising a chamber in which gas may be exploded, a gas generating chamber adjacent to one end of the explosion chamber, a removable water container, a source of gas liberating material mounted on the cannon, a measuring device for admitting measured quantities of said material to the water container, means permitting the transfer of the gas in said gas generating chamber developed by the reaction of the water with the material, into the explosion chamber, and means for interrupting communication between the chambers before the gas is ignited in the explosion chamber.

11. In a toy cannon, in combination, a gas forming chamber having a removable water container, a container on the cannon for gas liberating material, and a measuring device between the material container and the chamber for admitting a measured quantity of the material into the water container.

12. In a toy cannon, in combination, a hollow tapered support, a hollow tapered breech block disposed within the support, and a removable container mounted below the breech and adapted to receive fluid, the level of which is above the end of the breech block.

13. In a toy cannon, in combination, a hollow tapered support, a hollow breech block disposed within the support, and a container mounted below the breech and adapted to re-

- ceive fluid, the level of which is above the end of the breech block.
14. In a toy cannon, in combination, a gas explosion chamber having a hollow tapered support adjacent one end of the chamber and an opening communicating with the chamber and the hollow support, a hollow tapered breech block disposed within said support provided with an opening disposed to register with the opening leading to the chamber when in one position, said breech block being arranged to close off communication between the hollow breech block and the chamber when in another position.
15. A tapered hollow breech open at one end, a magazine disposed in the other end, and means cooperating with the magazine for admitting gasifying material from the magazine into the breech block.
16. In a toy cannon, a hollow breech block, a removable water container disposed at one end of the breech block and a measuring device disposed intermediate the water container and the other end of the breech block.
17. In a toy cannon, a hollow breech block, a removable water container disposed in communicating relation with the breech block and a measuring device disposed intermediate the water container and one end of the breech block.
18. A hollow breech block having a storage receptacle for gas liberating material, and a measuring device for said material disposed between the receptacle and one end of the breech block.
19. In a toy cannon, a hollow breech block, a removable water container disposed in communicating relation with the breech block, and a manually operable measuring device disposed intermediate the water container and one end of the breech block.
20. In a toy cannon, a hollow breech block, a removable water container disposed at one end of the breech block, and a manually operable measuring device disposed intermediate the water container and the other end of the breech block.
21. In a toy cannon, in combination, a support, a hollow tapered breech block supported thereby, and a liquid sealing device removably disposed at one end of said breech block.
22. In a toy cannon, in combination, a support, a hollow tapered breech block supported thereby, and a liquid sealing device disposed at one end of said breech block.
23. In a toy cannon, in combination, a hollow tapered support, a hollow tapered breech block disposed within the support, and a liquid sealing device removably disposed at one end of the breech block.
24. In a toy cannon, in combination, a hollow tapered support, a hollow tapered breech block rotatably disposed within the support, and a liquid sealing device removably disposed at one end of the breech block.
25. In a toy cannon, in combination, a hollow tapered support, a hollow tapered breech block disposed within the support, a magazine for gas liberating material mounted on one end of said breech block, and a fluid container removably disposed at the other end of the breech block.
26. In a toy cannon, in combination, a support, a hollow breech block rotatably supported thereby, and a liquid sealing device removably disposed at one end of the breech block.
27. In a toy cannon, in combination, a support, a hollow breech block rotatably supported thereby, and a liquid sealing device disposed at one end of the breech block.
28. In a toy cannon, in combination, a hollow support, a hollow breech block rotatably disposed within the support, and a liquid sealing device removably disposed at one end of the breech block.
29. In a toy cannon, in combination, a hollow support, a hollow breech block disposed within the support, a magazine for gas liberating material mounted on one end of the breech block, and a fluid container removably disposed at the other end of the breech block in sealing relation therewith.
30. In a toy cannon, in combination, a hollow support, a hollow breech block rotatably disposed within the support, a magazine for gas liberating material mounted on one end of the breech block, and a fluid container removably disposed at the other end of the breech block in sealing relation therewith.
31. In a toy cannon, in combination, an explosion chamber, a touch-hole for said chamber, a gas forming chamber disposed to admit gas to the chamber, and means covering said touch-hole when the gas forming chamber is in gas admitting relation with the explosion chamber.
32. In a toy cannon, in combination, an explosive chamber, a touch-hole for said chamber, a gas forming chamber disposed to admit gas to the chamber, means covering said touch-hole when the gas forming chamber is in gas admitting relation with the explosive chamber, and means arranged to interrupt communication between the gas forming chamber and the explosive chamber when the touch-hole is uncovered.
33. In a toy cannon, in combination, an explosive chamber having a gas admitting port, a chamber having an opening disposed to register with the explosive chamber port when gas is generated in said chamber, and means for closing said explosive chamber port.
34. In a toy cannon, in combination, an explosion chamber having a gas admitting port in a wall thereof, and a hollow breech block having an opening disposed to register with said port when the block is in one position,

and to close said port when in another position.

35. In a toy cannon, in combination, an explosion chamber having a gas admitting port in a wall thereof, a hollow breech block having an opening disposed to register with said port when the block is in one position and to close said port when in another position, and a container for fluid removably disposed at one end of said breech block in fluid sealing relation therewith.

36. In a toy cannon, in combination, an explosion chamber having a gas admitting port in a wall thereof, a hollow breech block having an opening disposed to register with said port when the block is in one position and to close said port when in another position, and a container for fluid disposed at one end of said breech block in fluid sealing relation therewith.

37. In a toy cannon, in combination, an explosion chamber having a gas admitting port in a wall thereof, a hollow breech block having an opening disposed to register with said port when the block is in one position and to close said port when in another position, a container for fluid removably disposed at one end of said breech block in fluid sealing relation therewith, and means at the other end of said breech block for admitting gas liberating material into said fluid container.

38. In a toy cannon, in combination, an explosion chamber having a gas admitting port in a wall thereof, a hollow breech block having an opening disposed to register with said port when the block is in one position and to close said port when in another position, a container for fluid disposed at one end of said breech block in fluid sealing relation therewith, and means at the other end of said breech block for admitting gas liberating material into said fluid container.

39. A cannon having an explosion chamber, and a rotatable hollow breech block, said breech block being disposed to permit communication between the chamber and breech block when in one position and to prevent communication when in another position.

40. In a toy cannon, a hollow breech block, a source of supply of gas liberating material disposed in communicating relation to the breech block, and a measuring device disposed between the source of supply and one end of the breech block arranged to admit measured quantities of said material into the breech block.

41. In combination, a gun barrel, closure means for the breech end of the gun barrel and turnable with relation thereto, a storage chamber in said closure means, a measuring chamber in said closure means, a discharge passageway from said measuring chamber to a point remote from the gun barrel, a water chamber in communication therewith remote from the gun barrel, a gas passageway con-

necting the water chamber and the gun barrel, and means for slidably and detachably supporting said water chamber for its removal, cleaning and replenishment.

42. A toy gas cannon embodying a supporting structure, a gun-barrel-structure having a closed breech end and a passage vertically through its rear portion, a water tank arranged under said passage to receive the gas-making materials as they fall through said passage by gravity, a closure for the upper end of said passage embodying a magazine for the gas-making material and also a measuring device for measuring a charge of gas-making material, this measuring device having a discharge opening arranged to discharge the gas-making material by gravity down through said passage into said tank, whereby when said discharge takes place the generated gas will rise directly into said passage in the gun-barrel-structure.

43. A toy gas cannon embodying a supporting structure, a gun-barrel-structure having a closed breech end and a passage vertically through its rear portion, a water tank arranged under said passage to receive the gas-making materials as they fall through said passage by gravity, a closure for the upper end of the said passage embodying a magazine for the gas-making material and also a measuring device for measuring a charge of gas-making material, this measuring device having a discharge opening arranged to discharge the gas-making material by gravity down through said passage into said tank, whereby when said discharge takes place the generated gas will rise directly into said passage in the gun-barrel-structure, said water tank being rearwardly removable from under the gun-barrel-structure.

In testimony whereof, I have hereunto subscribed my name this 1st day of June, 1928.

JOHN W. MacDONALD.
